UNITED STATES PATENT OFFICE.

EBENEZER SPERRY, OF MIAMI VILLAGE, KANSAS.

TOY GUN.

Specification forming part of Letters Patent No. 66,531, dated July 9, 1867.

To all whom it may concern:

Be it known that I, EBENEZER SPERRY, of Miami Village, in the county of Miami and State of Kansas, have invented a new Toy and Harpoon Gun; and I do hereby declare that the following is a full and clear description thereof, reference being had to the accompanying drawings, and to the letters of reference marked thereon.

Figure 1 of the drawings is a top plan of the improved gun. Fig. 2 is a side elevation of it. Fig. 3 is a longitudinal vertical section of the same.

This invention consists in the employment of a gun-barrel in connection with a plunger and elastic springs, the springs being arranged so as to draw the said plunger forward with great violence as soon as the trigger releases the plunger at the breech of the piece. There are arms attached to the plunger, and projecting outside of the barrel, which is slotted nearly its entire length for their passage, the said arms being used for the attachment of the aforesaid elastic springs to the plunger.

To enable those skilled in the art to make and use my improved gun, I will proceed to describe its construction and operation.

A is the gun-barrel, and B is the wooden stock. C is the plunger or follower, to which the springs D are applied, to draw it forward.

The plunger is a cylindrical piece of metal, having arms e e, which project through slots a a in the sides of the gun-barrel, the said slots being long enough to accommodate the whole longitudinal motion required of the plunger. The cylindrical cavity c¹ of the plunger should be of the same caliber as the bore a¹ of the muzzle of the gun-barrel, which is contracted at the square shoulder a² to the proper size, the said square shoulder serving to stop the forward motion of the plunger.

The springs D are simply india-rubber bands, or some similar elastic material, hooked over the arms a³, projecting from the sides of the gun-barrel, near its muzzle, and over

the arms c c, projecting from the sides of the plunger.

A strap, c², either of metal or of some pliable material, as leather, attached to the plunger C, is hooked over the detent E, which forms the principal part of the lock of the piece. This detent is an L-shaped piece of metal, as clearly shown in Fig. 3, is pivoted to the stock at e, and has a small arm, e¹, to which the strap c² is hooked when the piece is prepared for a discharge.

The lower end of the detent E is shaped as shown by e² in Fig. 3.

The guard F is permanently fixed at f and f¹, but acts as a spring at the point f².

When, now, the gun is ready for discharge, the spring guard-plate holds the end e² of the detent E in the one position shown in Fig. 3. Then, to fire, the trigger E' is drawn back to the other position shown, thus depressing f² and releasing the end e² of E, and the detent is then simply drawn down by the elastic force of the bands D acting through c²; thus e² is released from E. But as soon as this takes place, the action of the spring F and the plate f² on e² is to press E into its original position, in which c² may again be passed over E, as originally done. A toy missile or a harpoon placed within the barrel previous to the discharge of the plunger will be thrown out with great force by its momentum.

This gun may be found very useful in throwing the harpoon; but in that case a slot (not shown) would have to be cut for the harpoon-line in the bottom of the gun-barrel.

The guard G is simply used to hold the back end of the barrel in place.

Having described my invention, what I claim is—

The combination of the detent E with the guard-spring F and check-piece f², and the trigger E', substantially as set forth.

EBENEZER SPERRY.
